UNITED STATES PATENT OFFICE.

IRA H. SPENCER, OF HARTFORD, CONNECTICUT, ASSIGNOR TO THE SPENCER TURBINE CLEANER COMPANY, OF HARTFORD, CONNECTICUT, A CORPORATION OF CONNECTICUT.

SUCTION CLEANER AND DUST-SEPARATOR.

1,114,059.

Specification of Letters Patent. Patented Oct. 20, 1914.

Application filed November 22, 1907. Serial No. 403,318.

To all whom it may concern:

Be it known that I, IRA H. SPENCER, a citizen of the United States, and a resident of Hartford, in the county of Hartford and State of Connecticut, (whose post-office address is Hartford, Connecticut,) have invented certain new and useful Improvements in Suction Cleaners and Dust-Separators, of which the following is a full, clear, and exact description, whereby any one skilled in the art may make and use the same.

The invention, as indicated by the title, relates to a cleaning apparatus, and more particularly to such a device having special inherent features of dust separation incidental to the mechanism for creating an air pressure or suction.

The present invention contemplates a cleaning device, in which the suction for drawing off the dirt is induced in a most efficient and economic manner and the suction apparatus employed in the device is practically unlimited, as to the volume of fluid drawn through the cleaning tools and at the same time maintains a substantially constant pressure or suction effect at the inlet or mouth of the cleaning tubes.

In devices of the prior art, so far as known, positive suction apparatus has been employed, including a "piston pump" or a "rotary piston pump or positive blower." Either of these devices give a variable vacuum or suction depending upon the contraction or closure of the opening or orifice through the cleaning tools. The present invention has to do with a non-positive suction apparatus so constructed that the requisite vacuum or suction to induce air pressure or suction is maintained at a substantially constant pressure with an unlimited volume of air passing through the apparatus. The term "non-positive" suction apparatus is employed herein in contradistinction to suction inducing apparatus, such as exhaust pumps of various types which include a piston and cylinder for exhausting air, gear pumps, eccentric vane pumps and, in fact, any device in which the suction is induced by co-operating parts, which fit closely and slide upon one another to give a positive induction and exaction. It is to be understood that the device herein de-

scribed induces or draws a current of air from the inlet or cleaning tools when the 55 orifice through said tools is not completely and perfectly closed, but when completely and perfectly closed, no air passes therethrough and the suction upon the closure, whatever it may be, will not increase: 60

The objects of the invention are to provide a simple and extremely efficient suction apparatus, practically unlimited as to the volume of air taken in by the mechanism, and with a substantially constant pressure or suction, and incidentally, a substantially constant degree of vacuum.

From the above, it will be seen that with the inlet tubes or tool orifices completely closed, there will be created a vacuum at 70 the inlet. This vacuum is always substantially constant inasmuch as the device is so arranged that the pressure or suction inducing apparatus will create a certain suction with a varying volume of fluid passing therethrough and even when the orifices are completely closed, the vacuum or suction will be substantially the same as when they are open. The conditions described are quite different where a positive suction device as, for instance, an exhaust pump is employed. In the latter instance, the closing of the inlet orifice causes the pump to increase the degree of vacuum, while with the orifices fully open, the suction or vacuum 85 effect at the cleaning tool orifices may drop below the proper working pressure.

A further object is to provide a suction apparatus which, while it creates the necessary pressure or vacuum, will automatically 90 throw off and separate all dust, dirt, or extraneous substances from the fluid passing through the suction inducing apparatus, as said fluid passes therethrough.

A still further object is to arrange a series of dust or dirt collecting devices which will separate from the vitiated or impregnated fluid debris of varying weights and densities as the fluid bearing said materials is passing through said apparatus.

A still further object is to provide, in connection with the suction and separating apparatus, positive extracting means and traps for collecting debris of varying consistency.

Referring to the drawings: Figure 1 is a

100

105

2
central longitudinal sectional view of the apparatus. Fig. 2 is an end view in elevation taken from the right of Fig. 1. Fig. 3 is a detail sectional view on enlarged scale showing a slightly modified form of collecting receptacles. Fig. 4 is a transverse sectional view on the line B—B of Fig. 3. Fig. 5 is a detail view of the bottom of one of the cleaning tools showing the slot or opening.

15 In the apparatus herein described particular attention has been given to securing a most efficient method, and apparatus for creating a substantially constant pressure or vacuum which will pass practically an unlimited volume of fluid impregnated to a greater or less extent with dust, dirt or moisture and at a substantially uniform pressure through the inlet orifice and 20 through the cleansing tools attached thereto. These tools are shown in Figs. 4 and 5 of the drawings.

25 The apparatus consists essentially of a multiple-stage turbine blower, or exhauster, of efficient design, and as shown herein, has a plurality of impellers each arranged in a separate compartment with deflectors for leading the air from the periphery of the impeller of one compartment through a central orifice into the next succeeding compartment, and arranging in connection with such a multiple stage turbine blower, or exhauster, receptacles or traps for receiving and collecting the material with which the 35 fluid is impregnated as it enters and is driven through the apparatus.

40 It is understood that it is old in the art to employ "positive suction apparatus" to secure a pressure or vacuum for cleaning tools attached thereto. In such devices including positive "piston pumps" and "rotary piston pumps or positive blowers" great difficulty has been experienced, not only by the necessity of placing intermediary water cleansers for the impregnated fluid, but also from the wear and uncertain 45 operation of said positive suction inducing mechanism through the wear due to the passage of grit to the closely fitted parts. A 50 further disadvantage has resulted in the use of such apparatus through the varying vacuum or pressure induced thereby. For instance, the piston pump or positive blower of a definite capacity will pass a specific volume of fluid at a given pressure. If, for any 55 reason the inlet area through the tools or dust collecting apparatus is varied, the pressure or vacuum is immediately varied. If the inlet areas are more or less restricted by 60 being held close to the fabric, or the floor, or are tilted to collect particles of greater or less size, the vacuum or pressure is immediately varied. If said tools are held firmly and closely upon a fabric, the vacuum 65 or pressure is increased to such a degree as

to injure the nap or texture of said fabric. If the inlet orifice of the cleaning tool is opened by lack of intimate contact with the fabric for the purpose of picking up larger particles of material, the vacuum or pressure is immediately decreased to such an appreciable extent that it will not cause proper cleansing. In other words, in all such positive suction inducing apparatus the device must first be of such a capacity as to 70 provide a known suction for the maximum cleaning effect, and if the orifice of the cleaning tools is decreased by contact with material to be cleaned, said vacuum or pressure will immediately increase to a dangerous extent. For instance, a positive exhaust pump, with its capacity determined by its cylinder and piston movement, will suck up and discharge a certain quantity of fluid with the inlet of a given size, if the inlet is restricted by partially closing it as, for instance, placing a cleaning tool upon a fabric, the suction upon the fabric will be increased and the more the inlet is restricted, the greater will be the suction. On the 80 other hand, it is impossible within the limits of practice to provide a positive suction apparatus of the class above defined which will permit the use of orifices in the cleaning apparatus sufficient to vary the conditions 85 of picking up small particles and very large particles or debris. Furthermore, in such apparatus the passage of dirt, dust or grit, whether wet or dry, through the apparatus seriously impairs its usefulness as the efficiency of the apparatus due to the cutting of the grit is seriously interfered with.

90 To overcome the objections hereinbefore noted, the present invention contemplates the use of a multiple stage turbine blower, 105 or exhauster, all the parts of which will receive, act upon and pass or throw off the particles with which the fluid is impregnated without the liability of endangering the efficiency of the apparatus. Substantially, such 110 a multiple stage, turbine blower, or exhauster, as forms a part of this invention, is shown and more particularly described as to detail in a co-pending application, Serial Number 376,608, filed May 31, 1907. In the 115 present invention, however, the multiple stage, turbine blower, or exhauster, is arranged to not only create an efficient pressure or suction for taking up the impregnated fluid, but automatically separates and 120 throws off all of the heavier particles which are contained in the impregnated fluid. It separates and throws off these particles as the fluid is carried through the apparatus, and the fluid is thus thoroughly clarified. 125 The arrangement is such that no matter how vitiated or impregnated the fluid may be upon entering the inlet orifice, clean, clear fluid is thrown out of the exhaust side of the apparatus.

Referring to the drawings and particularly to Figs. 1 and 2 thereof, there is shown a casing 1 of cylindrical form, having headers 2-3 preferably provided with 5 central journal boxes 4-5, affording a support for anti-friction bearings 6-7 for the main blower shaft 8. In the journal box 4 there is arranged a thrust bearing 9 which is made adjustable and takes up all thrust 10 upon the end 10 of the shaft, thereby maintaining a proper and efficient running position for the various impellers. Upon the shaft 8 there are mounted a plurality of hubs 11, secured to which are disk-like 15 plates 12 having extending at right angles from the face thereof a series of blades 13. These constitute the impellers, and of course, they may be varied in number depending upon the degree of vacuum or pressure desirable 20 and the volume of fluid to be passed through the apparatus.

Secured to the casing 1 are disk-like plates 14 conforming in general contour to the shape of the impeller blades and bearing 25 on the opposite face from said impeller blades a series of deflector plates 15. These plates 15 extend radially of the plates 14 and are curved, as shown in Fig. 4, from the inner periphery of the casing 1 toward 30 a central orifice 16 formed about the center of the disks 14. These openings afford communication from one impeller chamber to the next succeeding chamber, and it will be noted that the disks 14 form chambers 35 within which the impellers may revolve.

At one end of the casing 1 is an intersecting casing 17 centrally arranged with reference to which is an inlet tube 18 to which may be connected any desired number 40 of inlet tubes and cleaning tools. This casing 17 is of cylindrical form, as shown herein, and has transversely arranged within it a cylindrical dust receptacle 19 which rests in a casing 20 of similar form, also arranged within the casing 17. The dust 45 receptacle 19 is of course open on the top and is provided with a handle 21 by which it may be withdrawn when it is desired to empty said receptacle. The casing 20 has an upwardly projecting neck 22 surrounding 50 the inlet tube 18 and somewhat larger in diameter than said tube. This necessitates the fluid entering the tube 18 making a short turn as it passes about the lower end 55 of the inlet tube 18 and up over the upper edge of the projecting neck 22 before it enters the chamber 23 of the casing 17. The parts described, thus form a trap for collecting the heavier particles which are carried 60 by the fluid as it passes therethrough. This chamber 23 is of course in direct communication with the casing 1 and its various impellers and the course of the fluid from the inlet through the impeller chambers, is 65 as indicated by the arrows. It will be noted

that said fluid passes from the periphery of the impeller of one compartment against the deflector blades arranged in said compartment and is then diverted by said blades through the center of the deflector blade 70 disk to the next succeeding impeller.

It will of course be readily understood that the fluid drawn into the apparatus passes through the various impeller chambers and through the exhaust side of the 75 device at comparatively low speed, although said fluid with its suspended materials is rotated very rapidly in each of the impeller chambers. It is also apparent that with the apparatus herein shown and described, 80 the pressure in each succeeding impeller chamber is raised beyond the pressure of the next preceding chamber. Therefore, there is a greater pressure within the last chamber than within the first, and consequently the fluid is kept moving through the device in a sufficient volume to effect 85 efficient work at the inlet nozzles or cleaning tools.

Only the heavier particles held in suspension by the incoming fluid are separated 90 therefrom and deposited in the receptacle 19. The lighter particles are drawn into the impeller chambers and rapidly whirled by the various impellers until they are 95 thrown off thereby, or forced into the final cleansing screen 33. As the impregnated fluid passes through the various impeller chambers it is given a very high rotary velocity and finally passes to the last impeller 100 24, where there being no deflector blades, said impeller 24 gives an extremely high rotary velocity to the impregnated fluid, throwing off all matter held in suspension, into the receptacle 25, shown herein 105 as located at one side of the impellers.

Arranged adjacent to the last impeller 24 is an annular disk 29, forming the end wall of the last impeller chamber. This has a central opening 30 of comparatively small 110 dimensions which compels a concentration of the revolving fluid and forms a vortex below the periphery of the impeller. Opposite the central opening of this annular disk 29 is a deflector plate 31 underlying a passageway or channel 32 which communicates with the interior of a positive collector or screen 33. The arrangement of the last impeller 24 with the vortex opening 30 is such that nothing but the very finest and 115 most insignificant particles, held in suspension by the fluid, are carried through said opening 30. All of the substantial particles are thrown off by the impeller 24 into the receptacle 25. This receptacle 120 25 is similar in form to the receptacle 19 and may be withdrawn by a handle 26 whenever the locking bolts 27 are released. It rests in an inclosed chamber 28 communicating with the interior of the casing 1. 125

The fluid which passes through the vortex opening 30 is deflected by plate 31 passing up into the interior of a screen 33 which is of cylindrical form and is supported from the top 34 of a cylindrical casing 35 provided with an exhaust opening 36 having a hand hole provided with a cover 37. The cylindrical bag-like screen 33 is open at its lower end and is secured at its bottom or 10 open end as at 38 and throughout its length is smaller in diameter than the casing 35, thus providing ample fluid space between the screen 33 and casing 35 and exhaust 36. Just below the open end of the screen 33 15 there is arranged a deflector plate 39 so located with reference to the opening 32 that the bag or screen 33 may be shaken to throw down any particles of dust or dirt which have collected therein. These particles will 20 thus be carried downward over the plate 39 and the plate 31 to the receptacle 25.

From the above description it is apparent that although heavy particles, such as metallic substances, and in fact everything 25 which is borne along by the rust of fluid without being held in suspension and forming a vitiated fluid will be caught in the receiving chamber 19. The finer though suspended particles of greater or less density 30 will be rapidly whirled through the apparatus from impeller chamber to impeller chamber, and by the centrifugal action of said impellers will be driven off, as illustrated in Fig. 1, by the last impeller 24 and 35 will be retained in receiving chamber 25. At this point the fluid is practically purified and only the very finest particles of dust 40 which would be hardly appreciable are carried through the vortex opening 30 and deflected upward and into the bag-like screen 33. This screen is preferably of woven form such as a fabric and of such a mesh and texture as to retain even the finest particles and is used more particularly to prevent the 45 passage of germs and particles which might be deleterious to health.

In practice the screen 33 needs little or no attention, and may from time to time be violently shaken by opening the hand hole 50 37, whereupon whatever particles are clinging thereto will be shaken down into the receptacle 25.

Of course it is understood, and in fact the drawings show that the centrifugal action 55 of the impeller blades may be employed at various points to secure a collection of the material carried in the fluid, and of course it is understood that various characters of fluid may be employed including not only 60 free or impregnated air but chemical fluids and others to suit the exigencies of any particular case.

Such an arrangement as above indicated with a number of collecting devices is shown 65 in Figs. 3 and 4 of the drawings, where the

impeller tools and intake casings and parts are substantially identical with those heretofore described. In these drawings the casing 100 is connected with the inlet chamber 101 which has a dust receiving chamber 102 and intake tube 103 as well as the screen chamber 104 and screen 105. There is also shown in connection with the intake tube 103 flexible collector tubes 103^a connecting with the dust collecting tools or hoods 103^a. The impeller chamber 106, annular deflector plates 107 and deflector blades 108 are substantially identical in form and arrangement with like parts described in connection with Figs. 1 and 2. At various points 70 adjacent to the casing 100 are arranged receiving chambers, illustrated in Fig. 3, as four in number and indicated at 109—110—111 and 112. These in each instance are inclosed chambers connecting with the respective impeller compartments 113—114—115 and 116. The receptacle 109 receives the particles thrown off by the first impeller 117, thus taking up the heavier particles. As the air is carried through the succeeding 80 impeller chambers less heavy particles are thrown off into receptacle 110 by the impeller 118. The next receptacle 111 receives still lighter particles from the impeller 119, and still lighter particles are thrown off by the impeller 120 into the receptacle 112, the impeller 120 practically clarifies the fluid passing pure air up to the screen 105, but whatever slight accumulation 90 may be retained by the screen 105 may be shaken down over the plate 121 into the receptacle 112.

From the above arrangement of receiving chambers arranged in connection with the rapidly rotating impellers, it will be seen that the device may be arranged to suit the exigencies of any particular case—for instance, in shop cleaning where it is desirable to reclaim filings and materials of different weights, the proper number of receptacles 105 may be arranged appurtenant to the most efficient impeller for reclaiming the particles of certain known weights and this arrangement precludes the possibility of injury to the blower by the heavier particles passing 110 therethrough. A still further practical advantage results from a segregation of the different materials no matter where the cleaning apparatus is used. By having the heavier particles accumulated in certain known receptacles articles of value picked up by the cleaning tools may be more readily found, and it will not require a sifting of 120 the whole mass and perhaps the more injurious or infectious dust and dirt.

The cleaning tools are only shown in connection with Fig. 4, although it is apparent that tools of various sorts may be applied to the device shown in either of the figures. These tools which are shown in Figs. 4 and 125 130

5, comprise a hood having an open slot 103^c at the under side through which the impregnated air and particles of various sizes may be drawn, and passing through tubular connections, find their way into the cleaning apparatus.

As to the possibilities and advantages of the herein described suction apparatus, the following facts are of interest: In a piston pump apparatus having a 12-inch piston and a 6-inch stroke running at 100 revolutions per minute and exhausting a vacuum measured at 15 inches of mercury, the apparatus will exhaust about 40 cubic feet of free air per minute when the pistons and valves are absolutely tight. The multiple stage turbine exhauster, herein described, using the same power, will exhaust over 500 cubic feet of free air per minute, and at the same time maintains a sufficient and constant vacuum for effective work. With such conditions it is possible to use a cleaning tool having a much larger inlet area than that which it is possible to employ with the positive piston pump apparatus. For instance, with the multiple stage turbine exhauster or non-positive suction device herein described it is possible to use a maximum slot opening of $\frac{4}{3}'' \times 10''$ or $\frac{3}{8}'' \times 30''$, thus giving a maximum inlet area for cleaning of $7\frac{1}{2}$ to $11\frac{1}{4}$ square inches. This is some five to nine times greater than the maximum permitted in practice with a positive piston pump or suction device such as referred to above, where the maximum slot is $\frac{1}{8}'' \times 10''$ or $12''$, with a maximum area of $1\frac{1}{2}$ square inches. It will also be seen that the apparatus herein described is particularly well adapted to and efficient for all classes of cleaning. It has a substantially free air passage from the collecting tool through the entire device to the retarding screen or final cleanser 33. Of course it has a trap for heavier articles or particles carried by the great volume of air, but dust and dirt, both wet and dry, may be carried practically through the apparatus, being separated by the centrifugal action as it moves and will not affect the retarding screen or final cleanser as the latter is at the outlet end and receives practically clear, clean fluid. Such an arrangement with the advantages of the final cleansing screen removed from all liability of injury through clogging, etc., is made possible by the use of the multiple stage turbine, which maintains a constant pressure or vacuum and throws off all deleterious matter from the fluid before said fluid passes through the final screen.

Obviously, the various details might be varied and changed to a considerable degree without departing from the spirit or intent of the invention.

The device herein shown and described is somewhat similar to the devices shown

and described in co-pending applications for cleaning apparatus and dust separator, Serial No. 403,317, filed Nov. 22nd, 1907, and method and apparatus for cleaning and separating dust, Serial No. 403,319, filed Nov. 22, 1907. This application, however, claims only the invention herein shown and described and forms no part of the specific details of the co-pending applications.

What I claim as my invention and desire to secure by Letters Patent is:

1. In a dust separating apparatus, a case having an inlet chamber, a closed dust receptacle opening out of the case, impellers rotatably mounted in the case, deflector plates secured within the case at a point adjacent to the opening into the receptacle, and means for decreasing the area of the opening from the impellers at the periphery thereof to accelerate the flow of fluid therefrom.

2. In a dust separating apparatus, a case having an inlet chamber, a dust receptacle opening out of the case, a deflector plate secured within the case adjacent to the edge of the opening into the dust receptacle, and an impeller having a wall arranged transverse to its axis, said wall and deflector plate converging at a point adjacent to the opening from the impeller case into the dust receptacle.

3. In a dust separating apparatus, a case having an inlet chamber, a dust receptacle opening out of the case, a deflecting plate extending in a direction oblique to the axis of said case and fixed thereto at a point adjacent to one edge of the opening into the dust receptacle, an impeller rotatably mounted in the case and having a wall arranged transverse to the axis of said case whereby the deflecting plate and wall of the impeller converge to a point adjacent to the opening into the dust receptacle to accelerate the flow of fluid and increase the separating action.

4. In a dust separating apparatus, a case provided with an inlet chamber and having a plurality of communicating impeller compartments connected with the inlet chamber, a series of rotary impellers located in said compartments for producing increased air pressure in each of the succeeding chambers, said case having a plurality of openings of material width through its wall located substantially in the plane of rotation of some of the impellers, and closed receiver chambers located opposite said openings and separated from the chamber within the case to receive material thrown off by said impellers through said openings.

5. In a dust separating apparatus, a case provided with an inlet chamber and having a plurality of communicating impeller compartments connected with the inlet chamber, said case having an opening located sub-

stantially in the plane of rotation of the impellers at each end of the case and also having openings located substantially in the plane of rotation of intermediate impellers, 5 and closed receiver chambers separated from the chamber within the case and in line with said openings to receive material

thrown off by the impellers through said openings.

IRA H. SPENCER.
